UNITED STATES PATENT OFFICE.

LEWIS T. WILCOX, OF PEEKSKILL, NEW YORK, ASSIGNOR TO WILCOX PATENTS CORPORATION, OF PEEKSKILL, NEW YORK, A CORPORATION OF NEW YORK.

RANGE.

Application filed January 19, 1926. Serial No. 82,193.

This invention relates to combined fluid and solid fuel stoves, and more particularly to the type popularly called a range.

An object of the invention is to provide an improved stove of this type which may be manufactured largely of sheet metal and fabricated parts; which may be assembled to have the oven at either the right or left hand end with a minimum of parts required; which may be assembled in a simple manner; which will be convenient, durable, attractive in appearance and simple and inexpensive in construction; and with which a common flue may be utilized for both the stove unit and fluid burner oven, and the smoke flue shut off when the fluid burner oven is in operation.

Various other objects and advantages will be apparent from the following description of one embodiment of the invention, and the novel features will be particularly pointed out hereinafter in connection with the appended claims.

In the accompanying drawing:

Fig. 1 is a front elevation of a range constructed in accordance with this invention;

Fig. 2 is an end elevation of the same; the elevation being that of the right hand end of the range of Fig. 1;

Fig. 3 is a sectional elevation of the same, the section being taken approximately along the line 3—3 of Fig. 1;

Fig. 4 is another transverse sectional elevation of the same with the section taken approximately along the line 4—4 of Fig. 1;

Fig. 5 is a longitudinal sectional elevation of a portion of the same with the section taken approximately along the line 5—5 of Fig. 6;

Fig. 6 is a sectional plan of the same with the section taken approximately along the line 6—6 of Fig. 1;

Fig. 7 is a sectional plan of a portion of the range at one corner of the shelf, the section being taken approximately along the line 7—7 of Fig. 2;

Fig. 8 is a sectional plan of a portion of the upright structure at one corner of the oven part, the section being taken approximately along the line 8—8 of Fig. 1; and

Fig. 9 is a section through a portion of the device, the section being taken approxi-

mately along the line 9—9 Fig. 1 and illustrating the manner of mounting the inner end of the fluid fuel supply pipe upon the inner face of the solid fuel burner unit.

In the illustrated embodiment of the invention, the base 1 is provided with the usual supporting legs 2. An upright structure 3 is mounted upon said base at one end thereof, and a solid fuel burner unit 4 is mounted upon said base at the other end thereof, both the upright structure and unit extending entirely from front to rear of said base. The upright structure 3 is provided in its upper part with an oven 5 of any suitable construction having the usual door 6 in the front thereof, through which access may be had to the baking chamber of the oven, the door in this example being hinged along its lower edge so as to swing forwardly and downwardly when opened. The hinge may be formed for example by passing a rod 7 (see Fig. 8) through the lower part of the door 6 and at both ends through a shoulered wall 8 forming the inner wall of the baking chamber. A suitable cotter pin 9 or the like may be passed through the rod 7 in the portion projecting through the wall 8 to lock the rod against withdrawal.

The solid fuel burner unit 4 may have the usual fire door 10 enabling the addition of fuel as required, and the usual ash pit door 11 and the shaker device 12. The fuel door 10 may be hinged along its forward edge so as to tip forwardly and downwardly when opened. A smoke flue bracket 13 is provided upon the rear face of the solid fuel burner unit, said bracket having a sleeve portion 14 over which a smoke pipe or conduit 15 may be fitted. The bracket part 13 may have incorporated therein a suitable damper 16 by which communication of the unit and flue pipe 15 may be largely established or broken.

The heat passing upwardly through the bottom wall of the oven portion of the upright structure, passes upwardly through the baking chamber and through apertures 17 in the inner top wall 8 thereof, and into the space between the two top walls, thence rearwardly through the top, then through apertures 18 into the space 19 between the two spaced rear walls of the upright structure.

A split elbow 20 is secured to the upright structure upon the rear face of the lower part of the oven portion, and communicates with the oven space 19 through an aperture 21. A deflector plate 22, preferably V-shaped, may be provided in the space 19 above the aperture 21 so as to deflect the hot gases passing downwardly in the space 19 to the sides thereof before admitting it to the aperture 21.

The split elbow 20 is connected by a flue pipe or conduit 23 (see Figs. 1 and 6) with the smoke conduit 15 that extends upwardly from the solid fuel unit. The smoke conduit 15 is provided with a circular connector boss 24 upon one side, and with an aperture in the portion covered by the boss, the flue of conduit 23 being in telescopic relation with said boss whereby the interior of the flue 23 or conduit 23 will be in communication through the boss 24 with the smoke conduit 15. The smoke conduit 15 will, of course, be connected to a chimney or the like. The flue or conduit 23 is provided with a plurality of small apertures 23^a (Fig. 6) disposed along its bottom wall and of an aggregate area at least equally that of the conduit 15, whereby any draft created in the flue 23 by the gases in the conduit 15, will not exhaust heat from the oven 5, but will merely draw in a volume of air through the apertures 23^a. This will not interfere with the passage of the hot gases from the oven 5 along the top of the conduit 23.

A stove top 25 having burner openings 26 therethrough is connected between the top of said unit and the side wall of the upright structure, and at a level substantially that of the surface of the unit. A bracket 27 is secured upon the top of the unit, at its outer side edge, and a back wall 28 is connected between the upright structure at one end and the bracket 27 and the unit at the other end, said back wall extending downwardly to the base and as high as the upper face of the upright structure 3. A shelf 29 may be connected to the upper end of the bracket 27 and to the upper end of a side wall of the upright structure so as to form a substantial continuation of the upper face of the upright structure. A warming hood 30 may be connected to the upright structure, the shelf 29, and the bracket 27, such warming hood having a rear wall 31 which extends upwardly from the back of the range and then forwardly over the shelf 29.

A container 32 for a source of liquid fuel is mounted by brackets 33 upon the outer side faces of the upright structure, and a pipe 34 extends from the lower part of said container downwardly to a slight extent and then through the upright structure and above the base to a point adjacent the solid fuel unit 4. The end of the pipe adjacent the unit 4 is closed by a cap 35 (Fig. 9)

which is received within an opening of a boss 36, secured in any suitable manner, such as by bolts 37, to a side face of the unit 4.

The pipe 34 is provided with upstanding branches 38, in the upper ends of which smaller pipes 39 are telescopically mounted and packed by suitable stuffing devices (not shown). The smaller pipes 39 carry fuel distributing arms 40 which radiate therefrom and conduct the fuel to burner wells 41 provided in the casing 41, the latter having suitable burner mechanism therein. Rack bars 42 depend from the radiating arms 40 and are slidably received between the arms 43 of two telescopically arranged channel strips 44, which channel strips embrace and are securely clamped to the upstanding branch pipes 38.

A shaft 45 extends transversely through the arms of each pair of telescopic channel strips and in front of the racks. Pinion segments 46 are fixed on said shaft in the planes of the rack bars and between the arms 43 of the telescopic channels. When the shaft 45 is rotated the rack bars will be elevated or lowered and, therefore, the pipe 39 will be lowered into or extended from the branch pipe 38, thus elevating or lowering the fuel well in the casing 41. The receptacle 32 is of the constant level type the inverted bottle 47 thereof discharging into the bottom of the receptacle automatically to maintain a constant level therein in a manner well known. Thus as the casing 41 is elevated or lowered, the effective oil level therein will vary, and as well known in the art the intensity of the flame from the burner will vary.

A separate burner is provided for each branch pipe 38, one burner being provided beneath the oven and within the upright structure, and one or more (two being shown) beneath the stove top 25 and in the space between the upright structure 3 and the solid fuel burner unit 4. The side walls of the upright structure are provided with vertically elongated apertures 48, through which the pipe with its branches 38 may be inserted, the pipe being confined to the upper end of each slot by plates 49 which are secured in any suitable manner, such as by screws or bolts, to both faces of each side wall of the upright structure. Such plates 49 may have notches in their upper ends which engage beneath the pipe 34 and hold it securely against vibration.

A plate or bar 50 is disposed across the front of the lower part of the upright structure and secured to the side walls thereof. The plate 50 is mounted at approximately the height of the shaft 45 which controls the activity of the burner in the upright structure, and the shaft 45 passes through and has bearing in the plate 50. The outer projecting end of the shaft 45 is bent angularly to form an operating crank arm 51,

and this crank arm cooperates with suitable character designations 52 and 53 representing "lighted" and "out" positions of the burner, so that one may know from the position of the crank arm 51 the condition of the burner.

A similar plate 54 is mounted between the solid fuel burner unit 4 and the upright structure, and the shafts 45 of the other 10 burners beneath the stove top 25 extend through and have bearing in this plate. This plate also carries the designations 52 and 53 which cooperate with the crank arm of the shaft 45 to indicate the condition of 15 each burner. A heat shield 55 may be mounted upon the outer side face of the upright structure to protect the fuel source in the bottle 47 and casing 32 from the heat of the oven and the burner in the upright structure. Pans 56 and 57 may be mounted upon 20 the base below the burners to catch any drip from the burners or from cooking utensils which may be boiling over. The pans may be removable to facilitate cleaning of 25 the same.

In order to eliminate the number of burners which are necessary for cooking purposes and in order to economize in the consumption of liquid fuel, the single burner may be 30 utilized for two cooking burners or grate apertures 26. The burners are disposed well toward the forward face of the range, and directly above each burner is a grate opening 26 having a grate 58. Immediately in 35 the rear and spaced therefrom is a second burner opening 26 having another grate 59 therein, the grate 59 having its ribs preferably extending above the grate opening so that when an object is resting thereon 40 the hot cooking gas may pass upwardly through the grate and along between the ribs, and then out from under the object or utensil resting thereon.

A heat distributing shell 60 is mounted 45 beneath each pair of burner or grate openings 26, and with the stove top forms a chamber which connects with the two grate openings. This shell 60 has an aperture 61 therein directly over the burner so that the 50 heat from the burner may pass upwardly into the chamber formed by the shell 60 and through the grate openings 26. If a vessel or object is resting upon the grate opening directly over the burner it will be heated, and 55 the excess hot gases instead of passing upwardly around the vessel and being lost, will pass through the chamber formed by the casing 60 and up through the other grate opening 26 to supply heat to an object resting thereon also. These two burner or grate 60 openings are thus supplied with heat from a single source.

The oven may have suspended above both 65 burner or grate openings thereof a heat deflector 62 which is concave from side to

side and inclined upwardly toward the rear, to cause a considerable portion of the heat from the forward burner which passes upwardly through the forward grate opening in the bottom of the oven, to be deflected 70 rearwardly and spread laterally by the heat deflector 62. Thus all parts of the baking chamber of the oven will be uniformly heated.

With a construction such as above described and illustrated, it will be obvious 75 that by utilizing the same parts, either a right hand or left hand range may be produced, merely by the assembly operation. In Fig. 1, this alternate feature is illustrated, the dot and dash positions illustrating the placing of the oven and coal burner parts at different ends. Thus in Fig. 1, the full lines indicate the appearance of a range of 80 the right hand type constructed in accordance with this invention, and the dot and dash lines indicate the changes in the assembly of a range when a left hand type of 85 range is desired. When the range is of the left hand type, the unit 4 will be at the left 90 hand end of the base, the upright structure at the right end and the other burners and burner top will be interposed between them as in this illustrated embodiment.

The smoke conduit 15 may be reversed 95 through 180° upon the bracket 13, so that it will afford a direct connection for the oven flue 23 when the oven and unit 4 are placed at the ends of the base opposite from that shown in Fig. 1. The range is made 100 practically entirely from sheet metal and fabricated parts which may be assembled as explained for either a right hand or left hand oven, so that practically no greater number of parts are required for the manufacture of both types of ranges. Such a range may be easily and readily assembled, and when so assembled will provide a very 105 practical and effective range, and one which is convenient and attractive in appearance. 110 The solid fuel burner and the fluid fuel burners may be used selectively or at the same time.

It will be obvious that various changes in 115 the details, which have been herein described and illustrated for the purpose of explaining the nature of the invention, may be made by those skilled in the art within the principle and scope of the invention as expressed in the appended claims.

I claim:

1. A combined fluid and solid fuel stove comprising a base, an upright structure mounted on said base at one end and having an oven in its upper part and a fluid fuel burner beneath the oven part, a solid fuel burner unit mounted upon said base at the other end, a burner top connecting said unit and upright structure, a fluid fuel burner disposed below said top to supply heat 120

therethrough, means for supplying fuel to said fluid fuel burners, said unit having a smoke conduit extending upwardly from its rear wall and having a damper therein, and a conduit connecting the oven part of the upright structure with the smoke conduit, said second conduit having apertures arranged along the length thereof, the total area of which is substantially equal to the cross sectional area of the second conduit.

2. A combined fluid and solid fuel stove comprising a base, an upright structure mounted on one end portion of said base and having an oven in its upper part and a fluid fuel burner beneath the oven part, a solid fuel burner unit mounted upon the other end portion of said base, a burner top connecting said unit and upright structure, a fluid fuel burner disposed beneath said top to supply heat therethrough, said unit having a smoke conduit extending upwardly from its rear wall and having a damper therein, and a conduit connecting the oven part of the upright structure with

the smoke conduit above the damper, said second conduit having apertures arranged along the bottom of the same.

3. A combined fluid and solid fuel stove comprising a base, an upright structure mounted upon one end portion of said base and having an oven in its upper part and a fluid fuel burner beneath the oven part, a solid fuel burner unit mounted upon the other end portion of said base, a burner top connecting said unit and upright structure, a fluid fuel burner disposed beneath said top to supply heat therethrough, said unit having a smoke conduit extending upwardly therefrom and having a damper therein, and a conduit connecting the oven part of the upright structure with the smoke conduit above the damper, said second conduit having apertures arranged along the length of the same.

In witness whereof, I hereunto subscribe my signature.

LEWIS T. WILCOX.
